United States Patent Office

Des. 183,133
Patented July 1, 1958

183,133

FOOD WARMING STAND

Michael S. Lax, New York, N. Y., assignor to Kromex
Corporation, Cleveland, Ohio, a corporation of Ohio

Application September 30, 1957, Serial No. 47,932

Term of patent 14 years

(Cl. D81—10)

Figure 1 is a perspective view of a food warming stand showing my design;

Figure 2 is a plan view thereof;

Figure 3 is a side elevation thereof;

Figure 4 is an end elevation thereof.

The burner element shown in broken lines in Figure 1 is for illustrative purposes only.

I claim:

The ornamental design for a food warming stand, substantially as shown and described.
